UNITED STATES PATENT OFFICE.

ALEXANDER H. COMMINS, OF AKRON, OHIO.

DESIGN FOR A FLOOR OR WALL COVERING.

SPECIFICATION forming part of Design No. 36,546, dated September 8, 1903.

Application filed June 6, 1902. Serial No. 110,653. Term of patent 14 years.

To all whom it may concern:

Be it known that I, ALEXANDER H. COMMINS, a citizen of the United States, residing at Akron, in the county of Summit and State of Ohio, have invented a new, original, and ornamental Design for a Floor or Wall Covering, reference being had to the accompanying drawing, which is a plan view of my design.

What I claim, and desire to secure by Letters Patent, is—

The ornamental design for floor or wall covering as herein shown.

In testimony whereof I have signed my name to this specification in the presence of two subscribing witnesses.

ALEXANDER H. COMMINS.
